UNITED STATES PATENT OFFICE.

FRANK SELZA, OF HARRISON, NEW YORK.

DOOR-JAMB SETTER.

1,003,517.

Specification of Letters Patent. Patented Sept. 19, 1911.

Application filed October 14, 1910. Serial No. 587,091.

To all whom it may concern:

Be it known that I, FRANK SELZA, a subject of the King of Italy, residing in Harrison, in the county of Westchester and State of New York, have invented certain new and useful Improvements in Door-Jamb Setters, of which the following is a specification.

My invention relates to devices for setting door-jams, and particularly to an attachment to such devices whereby the mortise of the door hinge may be located in position and cut by means of guides which insure the correct cutting of the mortise.

My invention consists in gages adjustable upon the door frame for the purpose of locating the position of the said mortise, and adjustable guides carried by the said gages for guiding tools employed to cut the mortise.

One practicable manner of employing my said invention is illustrated in the accompanying drawings, wherein—

Figure 1 is a plan view of a door-jamb setting frame illustrating my invention applied thereto. Fig. 2 is a cross-section on the line 2—2 of Fig. 1. Fig. 3 is an enlarged face view of parts of the frame illustrating the tool-guiding means for cutting the depth of the mortise. Fig. 4 is a view similar to Fig. 3, the parts of the frame there shown being omitted, and illustrating tool-guiding means for cutting the width of the mortise. Fig. 5 is a view of part of the frame. Fig. 6 is a cross-section on the line 6—6 of Fig. 5; and Fig. 7 is a detail section on the line 7—7 Fig. 4.

My invention may be employed in connection with any suitable door-jamb setting frame. As illustrated it is applied to such a frame, which I will designate as a whole by the letter A, which has relatively adjustable parts. Said frame is composed of uprights a^1 , each of which is of two pieces relatively adjustable or extensible through a tongue a^2 having beveled edges which are received in an undercut groove a^3 of the opposite part of the upright, as seen in Fig. 6. A set screw a^4 , holds the two parts of the upright when adjusted in position. Upright a^1 is similarly equipped with tongue, groove and set screw. These uprights are connected by cross-braces a^5 , a^6 which are also extensible, and are similarly provided with tongues and grooves and set screws to permit such extension. Said frame is

equipped with levels a^8 , a^9 for plumbing the frame.

As convenient means for holding the hinge-setting devices I may construct channels a^7 upon the outer sides of the uprights a^1 . These channels are located at about the position the hinge will come and are of sufficient size to provide a reasonable margin for the location of such hinges. Within these channels where they are employed I locate the devices for determining the position of the hinges and for guiding the tools in cutting the mortise. These devices constitute my invention. As shown the said devices comprise gages B of which I prefer to employ a pair for each hinge, and as the gages in each pair are similar in construction I will describe one of them. Each gage B is adjustable up and down or lengthwise of the frame A, and relatively to its mate and has means provided for the purpose of permitting such adjustment and of securing the gage in position in said frame, which as illustrated comprise a tongue b^1 which enters an undercut groove b^1 in the frame, whereby the gage is held in position and is permitted to slide up and down in said groove. A set screw b^2 may be provided to retain the gage in adjusted position. The gage is preferably equipped with an arm b^3 which is arranged parallel with the face of the frame, and serves to embrace the end of the door-jamb C. This arm on its outer face has an undercut groove b^4 within which slides a block b^5 . A set screw b^6 passes through a slot b^{20} in said slide, serving to hold it in position. Upon this slide is mounted a pin b^7 and a tool guide b^8 is slotted at b^9 , b^{10} , and the said slots receive upper and lower pins b^7 .

The inner horizontal edges of the arms b^3 as shown may be beveled at the top to allow the chisel to slip easily off same and prevent the dulling of the chisel. Below the beveled portions said edges are straight edges which serve to guide the tool in making the upper and lower cuts for the depth of the hinge, and the inner or left hand edge of the tool guide b^8 as shown has also a straight edge and serves to guide the tool in making a vertical cut for the depth of the mortise. The gage B is also preferably provided with a rearwardly extending arm b^{11} , seen in enlarged view in Fig. 4, which is perpendicular to the arm b^3 and embraces the face of the door-jamb C or that part of

it which lies opposite the door. This arm 5 b^{11} is illustrated as similarly provided with a groove b^{12} , carrying a sliding block b^{13} which is held in said groove and slides therein and is slotted at b^{14} to receive the shank of set screw b^{15} which secures the said block in adjusted position. Said set screw may be of sufficient length to screw into the door-jamb and hold the gage and frame in place. A tool guide b^{30} is slotted 10 at b^{16} and b^{17} , and these slots receive pins b^{18} which are carried upon the block b^{13} . The tool guide b^{30} , as also the tool guide b^8 , are adjustable in and out upon the said arms, and the slots contained therein permit the adjustment of the arm of the gages 15 B relatively to each other. The inner opposite edges of the arms b^{11} are straight edges for locating the position of the upper and lower sides of the hinge and constitute tool guides for cutting the mortise at such points. They may be beveled at their upper edges as are arms b^8 . The inner face of the tool guide b^{30} also locates the width of the 20 mortise for the hinge and constitutes a guide for the tool employed to make such cut.

In operation the frame A may be laid 25 upon the floor and the door-jamb secured to the outer parts thereof in any suitable manner, as by clamps if desired; the frame and door-jamb will then be erected in position in the doorway as usual and trued up by means of the levels, the usual blocks being inserted if necessary for the purpose of holding it plumb. After the door-jamb has been secured the gages B may be adjusted 30 to the position which it is desired the hinge shall have. The set screws b^{15} may then be screwed on the jamb. The arms b^8 will then be at the side of the jamb C and the arms b^{11} at the face thereof. The set screws b^6 may then be loosened and the slides b^5 35 adjusted so that tool guide b^8 will indicate the proper depth for the hinge when the said set screws will be tightened. Slides b^{18} will then be adjusted until the tool guide b^{30} shall indicate the proper width of the mortise for the hinge. A chisel may then 40 be employed against the straight edges of arms b^{11} and tool guide b^{30} to make the cuts in the face of the jamb for the hinge mortise, and suitable chisels against the straight edges of arms b^8 and tool guide b^8 to remove the said material to a proper depth. The 45 tool guides b^{30} and b^8 may be held upon their supporting pins by set screws if desired.

While I have illustrated my invention as applied to an adjustable door-jamb setting frame in connection with which it is extremely useful, I do not regard it as limited 50 in its application to such construction of frame, nor is it to be understood by reason of the particularity with which I have described the construction of my improved gage and the manner for permitting the ad-

justment of the various parts and securing the same in position, that I regard my invention as necessarily limited to these particular details, as equivalent means may be employed without departing from the spirit 70 of the invention.

What I claim is:—

1. In combination with a door-jamb setting frame, a gage adjustably mounted thereon to indicate the position of the hinge, 75 and comprising arms arranged at substantially right angles to each other, a tool guide mounted on each arm and adjustable relatively to its arm toward and from the meeting point of said arms for indicating the 80 cuts for the hinge mortise.

2. In combination with a door-jamb setting frame, a pair of gages independently adjustable thereon to indicate the position of the hinge, each gage having a pair of 85 arms arranged substantially at right angles to indicate the top and bottom cut for the hinge, and one set of arms having adjustable means for indicating the cut for the depth of the hinge, and the other set of arms having adjustable means for indicating the cut 90 for the width of the hinge.

3. In combination with a door-jamb setting frame, a pair of gages adjustably mounted thereon to indicate the position of 95 the hinge, and each gage comprising a pair of arms arranged at substantially right angles to each other, a tool guide adjustably mounted on each pair of arms and adjustable relative to said arms for indicating the 100 cuts for the hinge mortise.

4. In combination with a frame for setting door-jams, a pair of gages adjustable on said frame to locate the position of the hinges, each of said gages having two arms 105 adapted to embrace the face and side of said door-jamb, a tool-guide adjustably mounted upon opposite arms adapted to indicate the depth of cut for the hinge and a second tool guide similarly mounted upon 110 the other arms adapted to indicate the cut for the width of the hinge.

5. In combination with a frame for setting door-jams, a gage adjustable on said frame, having a pair of arms arranged rectangularly with respect to each other, and a tool guide upon each of said arms, each of said tool guides being independently adjustable toward and from the meeting point of 115 said arms.

6. In combination with a frame for setting door-jams, a pair of gages adjustable with respect to each other on said frame, arms on each gage adapted to extend over the side of the jamb, and a tool guide mounted on said arms so as to permit their adjustment relative to each other, and adjustable longitudinally of said arms, arms on each gage adapted to extend over the face of the 125 jamb and a second tool guide on said arms 120

mounted similarly to said first-mentioned tool guide.

7. In combination, an adjustable frame for setting door-jambs, a pair of gages mounted in said frame and independently adjustable, arms projecting from each gage, a block adjustably mounted in each arm, a tool guide carried by said block and adjustable therewith and thereon.
- 10 8. In combination, an adjustable frame for setting door-jambs, a pair of gages mounted in said frame and independently adjustable, arms projecting from each gage, a block adjustably mounted in each arm, a tool guide carried by said blocks and adjustable therewith and thereon, a second pair of arms projecting from each gage at right angles to said first-mentioned arms, and having similar blocks and a similar tool guide.
- 15 9. In combination, a frame for setting door-jambs having relatively adjustable
- parts, and having uprights with channels therein, a pair of gages mounted in each channel and independently adjustable therein, an arm projecting outward from each 25 gage, an adjustable slotted block in each arm, and a set screw for securing same in adjusted position, a pin in each block and a slotted tool guide supported on the pins of opposite arms, a second arm projecting 30 at right angles to said first-mentioned arm from each gage and having similar blocks and tool guide.

In witness whereof, I have hereunto signed my name in the presence of two sub- 35 scribing witnesses.

FRANK ^{his} X SCELZA.
